UNITED STATES PATENT OFFICE.

DON E. KEENEY, OF FLINT, MICHIGAN, ASSIGNOR TO A C SPARK PLUG COMPANY, OF FLINT, MICHIGAN, A COMPANY OF MICHIGAN.

INSTRUMENT PANEL.

Application filed July 15, 1927. Serial No. 205,976.

This invention relates to an instrument panel of the type ordinarily mounted on the dashboard of an automotive vehicle.

It is an object of this invention to provide an instrument panel which is simple in construction and hence economical to manufacture and which provides a firm support for any of the instruments usually carried on the dashboard. It is a further object of the invention to provide an instrument panel in which the front cover plate may be readily removed, thus providing easy access to any of the various instruments.

Other objects of the invention will appear in the course of the following description, taken in connection with the accompanying drawing and appended claims.

In the drawing:

Figure 1 is a front view of my improved instrument panel, with parts broken away.

Figure 2 is a section on the line 2—2 of Figure 1.

Referring to the drawing the numeral 10 indicates the substantially rectangular panel which is dished as illustrated and is provided about its rim with the bezel 12. A projecting flange 14 is provided about the periphery of the panel for fitting the panel within a correspondingly shaped aperture in the dashboard 16. The bezel 12 is provided on three sides with a channel 18 and on the fourth side, the upper in the present case, the channel is cut all the way through the bezel to form a slot permitting a cover plate or front element to be inserted by sliding the same in a plane parallel with the body of panel 10. At 22 I have illustrated the cover plate or front element which may be slid in through the slot to fit in the channels 18.

At 24 I have indicated an aperture in the panel adapted to fit the instrument bezel on the front of the instrument case 26. The case 26 preferably rests against the plate 22 and may be held in fixed position by a clamp 28 shown as fastened by screws 30 to the rear side of the panel. An aperture or apertures 32, opposite one or more of the apertures 24 and corresponding to the position of any

instrument or instruments 26, may be provided in the plate 22, a reduced portion or portions of said instrument or instruments being preferably permitted to extend through said plate, substantially as shown in Fig. 2, for an interlocking effect which normally holds said plate against relative sliding movement.

While I have illustrated in detail the mounting of but a single instrument, I desire it to be understood that any usual number of instruments may be supported in like manner by providing apertures in the panel corresponding to the size and shape of the instrument to be supported. The panel may be fixed to the dashboard in any usual or desired manner.

I claim:

1. In an instrument panel, a dished supporting element provided with a rim having a slot therethrough, a cover element slidable through said slot and substantially parallel with the body of said supporting element, one of said elements being provided with an aperture and means for holding an instrument supported in said aperture.

2. In an instrument panel, a dished supporting element comprising a bezel having a slot cut therethrough, a cover plate slidable within said slot there being an aperture in said supporting element, and means for holding an instrument supported in said aperture against said cover plate.

3. In an instrument panel, a dished supporting element provided with a slot, a cover plate slidable therethrough in a plane parallel with the body of said element, there being an aperture in said cover plate opposite an aperture in said supporting element, an instrument fitting within the aperture in the supporting element, and means on said supporting element for holding said instrument against said cover plate.

4. In combination with a dashboard having an aperture therein, a dished supporting element provided with a flange fitting against said dashboard, a slot in said supporting element adjacent said flange, a cover plate slid-

able in said slot and registering with the edge of the dashboard when the supporting element is in position thereon, and an instrument carried by said supporting element.

5. In an instrument panel organization: a dished element provided with a bezel; a cover element initially slidable relatively thereto;

an instrument adapted to extend through one of said elements; and means rendering a positioning of said instrument effective to interlock said elements against relative sliding movement in substantially parallel planes.

In testimony whereof I affix my signature.

DON E. KEENEY.
